HAT STAY

Joseph E. Jubin, New Orleans, La.

Application June 26, 1946, Serial No. 679,500

4 Claims. (Cl. 206—9)

1

This invention relates to hat stays for properly centering and positioning hats in boxes or containers, and constitutes an improvement in stays of the type disclosed in Patent No. 2,115,633, granted April 26, 1938 to Joseph G. Huye, wherein the hat is maintained against vertical displacement solely by frictional engagement with portions of the stay.

The primary object of the present invention is to provide a hat stay wherein locking means are provided to abut against the upper edge of the sweat band of the hat to positively prevent vertical displacement thereof, even though the stay and hat are inverted and subjected to jarring and rough handling such as may be expected in the shipping and handling of the hats.

Other more specific objects are: to provide such locking means which may be adapted for use with a collapsible stay; to provide such locking means which may be resiliently laterally compressed or confined while passing through the sweat band of a hat, to expand laterally into vertical registry with portions of said sweat band after having passed vertically therethrough; to provide means associated with said locking means for limiting the lateral expansion thereof to prevent harmful engagement with the interior of the hat crown; and, to provide in association with such locking means, centering means for maintaining the hat against lateral displacement.

A further object is to provide a hat stay embodying the above objects and advantages which may be simply and inexpensively formed from an integral flat blank of cardboard, pasteboard or other usual stiffly resilient material.

The foregoing, as well as other objects and advantages hereinafter appearing, are attained by the preferred embodiment of the invention illustrated in the accompanying drawings, in which:

Figure 1 represents a perspective bottom plan view of a form or blank which may be folded to form the preferred form of stay embodying my invention;

Figure 2, a perspective view of a stay formed from the blank shown in Figure 1, as same would appear when applied to an anchoring or separating member, such as a box bottom or a separating board to be placed in a box; and

Figure 3, a longitudinal vertical sectional view showing the stay as used in a box, a hat being applied to said stay as shown in dotted lines.

Referring now in detail to the accompanying

2

drawings, A designates a separator or separating board to which the stay may be secured for use in the manner set forth in the aforementioned Huye Patent 2,115,633; A' designates a paste board or paper board or other box bottom to which the stay may alternatively be secured; B, the body of the box; C, the top of the box; F, a felt hat held in arranged position by the stay; and, S, the usual sweat band of said hat.

10 Broadly the stay of the present invention comprises a central stay body which is adapted for attachment to a supporting surface, such as the upper surface of the separator A or the box bottom A', together with laterally oppositely 15 projecting pairs 6—6 of vertically disposed resilient sheet material centering and locking members.

Although the central stay body may assume various forms, so long as it provides means for 20 anchoring and supporting the flaps or members 6, I prefer to apply my present invention to the collapsible hat stay shown and described in Patent 2,115,633 to Joseph G. Huye.

Thus, the central stay body illustrated in the 25 accompanying drawings is identical with the corresponding portion of the invention illustrated in said Huye patent, comprising a top panel 1 formed with a finger-pull opening O, the side panels or sides 2 with attaching tabs 4, and 30 end panels or ends 3 with attaching tabs 5. The blank is scored along the sides of the panel 1, as at 9, and across the ends thereof, as at 9', the sides 2 being scored midway between the score lines 9 and the tabs 4, as at 10, and the 35 ends 3 being similarly scored midway between the score lines 9' and the tabs 5, as at 10'. The joints between the tabs 4 and sides 2 are scored as at 11, and the joints between the tabs 5 and the ends 3 are similarly scored as at 11'.

The centering and locking members 6 may be 40 formed integral with the sides 2, in such a blank as shown in Figure 1, by forming said members 6 as lateral extensions or projecting end portions of their respective sides 2, each said member 6 preferably being cut away along a slanting line 6' along its upper corner to avoid interference in the application of a hat to the erected stay.

Where said members 6 include both upper and 45 lower flaps or wings or portions 7 and 8 respectively, as in the preferred embodiment illustrated, said upper and lower portions 7 and 8 of each member 6 may be connected along a score or fold line which constitutes a continuation of the score line 10 in its respective side of the stay body,

3
thus rendering the stay collapsible and erectible in the same manner as in the aforementioned Huye Patent 2,115,633. The upper portion or wing 7 of each member 6 projects beyond the lower portion 8 thereof and is provided with a lower laterally extending locking edge 7'.

The stay may be formed from the above described blank in the manner set forth in the aforesaid Huye patent, the erected stay having an appearance similar to that illustrated in Figures 2 and 3, the procedure for forming the stay from said blank being briefly summarized as follows:

With the blank in inverted position, as shown in Figure 1, the outer portions of the sides 2 will be folded back along the score lines 10 to have the tabs 4 thereof lie flat against the lower face of panel 1. The ends 3 will be folded inwardly toward each other on the score lines 9' to lie flat against the lower face of the panel 1 and will then be folded outwardly away from each other on the score lines 10', whereupon the tabs 5 will be folded inwardly on the score lines 11' toward each other. The tabs 4 and 5 may then be pasted or secured by other suitable means to the face 15 of a separator A or box bottom A'.

The stay thus formed is in collapsed or flat condition and may be erected by inserting a finger through the finger pull opening O and lifting the top panel 1 vertically relatively to the separator A or box bottom A', whereupon the upper and lower, or inner and outer portions, of the side and end panels 2 and 3, on opposite sides of the score lines 10 and 10' respectively will lie in vertical planes. The stay may be maintained in erected condition by bending the end portions or members 6 of each pair towards each other, whereby the lower edges of the portions 8 thereof will engage the upper surface of the separator A or box bottom A', out of alignment with the score lines 11 of the sides 2, as shown in Figure 2.

In the use of the invention, with the stay erected, the members 6 at one end of the stay are pressed towards each other while at hat F is slantingly applied to receive said end of the stay in one end portion of its crown. Then the other members 6 at the opposite end of the stay are pressed inwardly toward each other and the hat moved downwardly over that end of the stay. As each end of the stay is received in the hat, the members 6 at said end are released, except as confined by the hat, and will by their resiliency spring outwardly to engage the interior of the hat.

Thereafter, during continued downward movement of the hat to the point where its brim rests on the upper surface of the separator or partition A or the box bottom A', as shown in Figure 3, the upper portions or flaps or wings 7 of the members 6 will pass completely vertically through and above the sweat band S of the hat, and will then expand or spread outwardly to have their outer free end portions and the locking edges 7' thereof lie just above and at least partially in vertical registry with their respective subjacent upper edge portions of the sweat band S.

Thus it will be seen that the upper portions or wings or flaps 7 function as locking means which, by abutting engagement of their lower locking edges 7' with the upper edge of the sweat band S, will prevent accidental vertical displacement or removal of the hat during handling or shipping of same, even though the containers or boxes are inverted.

At the same time, in the preferred form of the

5
invention the lower portions or flaps 8 of the members 6 function as the primary centering means, engaging and expanding or pressing resiliently against the interior of the sweat band S to center the hat F on the stay and prevent lateral displacement thereof.

Further, when used in connection with felt hats F or other hats which might be damaged or disarranged by outward pressure of the locking means 7 against the interior of the hat crown above the sweat band S, the vertical free end edges 8' of the centering flaps 8 may be offset rearwardly such a distance relative to the vertical free end edges of the locking flaps or means 7, as to engage the sweat band S after the respective integrally connected locking flaps 7 have sprung outwardly above the sweat band S and in vertical registry therewith, to limit such outward expansion of the locking flaps 7 and possible harmful pressure thereof against the interior of the hat crown.

However, while the foregoing arrangement constitutes a novel and advantageous feature of the invention, the invention is not limited thereto, nor is the invention limited to use with a collapsible stay body.

For instance where it is not necessary to prevent pressure of the locking flaps 7 against the interior of the hat crown, as when used with straw or other hats which would not be damaged or disarranged thereby, the lower flaps 8 could be either disconnected from the upper flaps 6, or else entirely omitted, in which case the locking flaps or means 7 would also function as the lateral centering means for the hat. In the latter case the score lines 10 and 10' would be omitted from the sides 2 and ends 3 of the stay structure to prevent collapse of same in the absence of the lower flaps 8, or any other type of stay body could be substituted as supporting and anchoring means for the wings or flaps 7.

In removing the hat from the stay, where the hat is of flexible material the flaps 7 may be pressed inwardly out of vertical registry with the sweat band S by pressure on the adjacent exterior portions of the hat. When the hat is of relatively stiff material, or when desired, same may be removed from the stay simply by lifting it with sufficient force to overcome the grip of the locking flaps or means 7.

Having thus described my invention, what I claim as new and desire to protect by Letters Patent is:

1. A hat stay comprising, a central stay body having a bottom disposed in a horizontal plane 55 to be anchored to a supporting surface, horizontally oppositely projecting pairs of vertically disposed stiffly resilient sheet material locking flaps attached at their inner ends to said stay body, said locking flaps being respectively formed with free lower locking edges parallel to and spaced above the plane of said bottom, the outer free ends of the locking flaps of each said pair being resiliently laterally compressible towards each other; in combination with vertically disposed stiffly resilient sheet material horizontally projecting centering flaps disposed below and attached to said respective locking flaps, the free outer ends of said centering flaps being relatively inwardly offset from the free ends of said respective locking flaps to engage the laterally inner surface of the sweat band of a hat applied to said stay.
2. A hat stay comprising, a central stay body 70 having a bottom disposed in a horizontal plane,

horizontally oppositely projecting pairs of vertically disposed stiffly resilient sheet material locking flaps attached at their inner ends to said stay body, said locking flaps being respectively formed with free lower locking edges parallel to and spaced above the plane of said bottom, the outer free ends of the locking flaps of each said pair being resiliently laterally compressible towards each other; in combination with means associated with said locking flaps to engage the inner surface of a hat sweat band to limit the lateral expansion of said flaps.

3. A hat stay comprising a central stay body having a bottom disposed in a horizontal plane, at least one pair of vertically disposed horizontally projecting stiffly resilient sheet material locking flaps connected at their inner ends to said stay body, said locking flaps being respectively formed with free lower locking edges parallel to and spaced above the plane of said bottom, the outer free ends of each said pair of locking flaps being resiliently laterally compressible towards each other.

4. A hat stay comprising, a central stay body having a bottom disposed in a horizontal plane, oppositely horizontally projecting pairs of vertically disposed stiffly resilient sheet material locking flaps attached at their inner ends to said stay body, said locking flaps being formed respectively with free lower locking edges parallel to and spaced above the plane of said bottom, and the outer free ends of the locking flaps of each said pair being laterally resiliently compressible towards each other.

JOSEPH E. JUBIN.
